UNITED STATES PATENT OFFICE.

JAMES G. MACLAREN, OF MAMARONECK, NEW YORK.

CARRIER-SORTING DEVICE FOR PNEUMATIC-DISPATCH SYSTEMS.

Application filed May 6, 1921. Serial No. 467,442.

To all whom it may concern:

Be it known that I, JAMES G. MACLAREN, a citizen of the United States, residing at Mamaroneck, in the county of Westchester 5 and State of New York, have invented certain new and useful Improvements in Carrier-Sorting Devices for Pneumatic-Dispatch Systems, of which the following is a specification.

10 This invention relates to carrier sorting devices for pneumatic-dispatch systems. Devices of this general nature for use in selectively separating carriers into two classes as they approach the outlet end of 15 the conveying tubes are well known in the art. Such separating devices ordinarily include positively operating carrier ejecting means connected through latching mechanism with a switch or gate, the latching 20 mechanism being operated or not in accordance with the conformation of an approaching carrier to control the interaction between the gate and the ejecting means and thereby determine through which of two outlets the 25 carrier will be discharged.

It has been found in practice that the use 30 of positively acting ejecting means has been open to the serious objection that the forcibly discharged carriers could not be effectively controlled and handled without the use of special shield or guard members. Furthermore the complicated nature of the mechanism which arose out of the use of the ejecting devices referred to, together 35 with the necessary accompanying spring members and other special parts, caused the apparatus to get out of order at frequent intervals with a consequent failure of the mechanism to perform its selecting function.

40 It is the object of this invention to provide a carrier sorting or separating device which will be free from the objectionable features referred to, and which will perform its function without the use of special means 45 for positively throwing the carriers into one of the discharge openings. The invention includes a gate member and means for latching the gate member in position across one of the openings in rigid connection with a stationary part to thereby cause the carriers 50 abutting thereagainst to topple from the rigidly-held gate into the other outlet.

In the drawing,

55 Figure 1 is a view in horizontal section of a carrier sorting device embodying a preferred form of the invention.

Figure 2 is a vertical sectional view of the device shown in Figure 1 and showing the device in one of its operating positions.

Figure 3 is a view similar to Figure 2 60 showing the device in the other operating position.

Referring to the drawing for a more detailed description, a tube section 1 is adapted to be introduced into and to form part of a 65 pneumatic dispatch tube. The tube section 1 is adapted to receive carriers at the upper inlet port 2 and is provided with a gate or deflecting member 3 which can be extended across the base of the tubular section to 70 cause the carriers to topple through the lateral discharge opening 4, or which can take a non-restricting position, as indicated in Figure 3, to permit the carriers to pass downward through the tubular section 1 and 75 through the lower outlet port 5.

The gate member 3 is mounted to rock on a pivot pin 6 mounted in and between a pair of bracket arms 7 projecting horizontally from the tube section 1 adjacent the upper 80 end of an opening 8 formed in the side of the tube section. The gate member 3 is provided at its outer end with a weight 9 which is preferably mounted between the side members of the sheet metal gate member 3. The 85 gate member is formed at its other extremity into an arm 10 which projects normally into the base of the tube section and is held in a substantially horizontal position 90 against the upper edge of the opening 8 by the action of the weight member 9.

Between the side members of the arm 10 a latch member 11 is pivoted on the pin 12 and is provided with a weight member 13 which tends to hold the hooked latch arm 95 14 of the latch member in engagement with the upper surface of a pin 15 mounted in a fixed position in the stationary bracket members 7 already referred to. The latch member is also provided with a forwardly 100 projecting arm 16 having an actuating lug 17 normally extending upwardly through a perforation 18 with which the arm 10 is provided.

In the operation of the device a descending carrier 19 having its ends provided with recesses 20 will engage the upper surface of the arm 10 in the manner indicated in full lines in Figure 2, but, as the recess 20 receives the lug 17, the lug 20 is not engaged or depressed with relation to the arm 10. The arm is thereupon swung to the

angular position indicated in dotted lines, further movement of the arm being prevented by the direct engagement of the hook 21 on the latch arm 14 with the stop pin 15.

5 It will be seen that the descent of the carrier in the tube is checked by the gate member 10 which swings to the inclined position shown in dotted lines in Figure 2 and is rigidly held in that position, the inclination of the gate being sufficient to cause the carrier to topple outwardly over the adjacent lower edge 22 of the discharge opening 4 in the side wall of the tube.

10 A carrier such as that shown at 23 in Figure 3 of the drawing which has a flash or non-recessed end will engage and depress the lug 17 with relation to the gate member 10, thereby tripping the latch member 14 and permitting the gate 10 to swing downwardly into the tube section and permit the carrier 23 to pass downwardly through the exit port 5, as will be clear.

15 It will be seen that the mechanism thus provided is positive and certain in its operation and that the carriers are caused to topple through the opening 4 with their momentum checked so that no guard or other protecting devices are required.

20 What is claimed is:

30 1. A carrier sorting device for pneumatic dispatch tubes comprising a tube terminal member having two outlet ports, a gate member normally extending across one of said outlet ports, and a latch carried by said gate member for directly engaging a fixed part of said terminal member and maintaining the gate in closed relation to said port, said latch permitting the gate to assume an inclined position to cause the carriers to topple outwardly about a pivotal point coincident with the base thereof and through the other outlet port.

35 2. A carrier sorting device for pneumatic dispatch tubes comprising a tube terminal member having two outlet ports, one of said ports being in line with the direction of travel of the carriers and the other port being located in the side of said terminal member, a gate member normally extending across said outlet port in the line of travel of the carriers, and a latch carried by said gate member for directly engaging a fixed part of said terminal member and maintaining the gate in closed relation to said outlet port in the line of travel of the carriers, said latch permitting the gate to assume an inclined position to cause the carriers to topple outwardly about a pivotal point coincident with the base thereof and through the outlet port in the side of said terminal member.

40 3. A carrier sorting device for pneumatic dispatch tubes comprising a tube terminal member having two outlet ports, one of said ports being in line with the direction of

travel of the carriers and the other port being located in the side of said terminal member, bracket members carried by said terminal member on the side opposite said lateral port, a gate member pivoted in said bracket members and normally extending across the outlet port of said terminal member in line with the direction of travel of the carriers, a latch carried by said gate member, and a latch engaging member carried by said bracket members, said latch being formed to engage said latch engaging member to thereby maintain the gate in closed position to said outlet port in the line of travel of said carriers, said latch permitting the gate to assume an inclined position to cause the carriers to topple outwardly about a pivotal point coincident with the base and through the outlet port in the side of said terminal member.

45 4. A carrier sorting device for pneumatic dispatch tubes comprising a tube terminal member having two outlet ports, one of said ports being in line with the direction of travel of the carriers and the other port being located in the side of said terminal member, bracket members mounted on the side of said terminal member opposite said lateral port, a gate member pivoted in said bracket members and extending into said terminal member, a weight for causing said gate member to normally maintain a position extending across the outlet port of said terminal member in line with the direction of travel of said carriers, a latch carried by said gate member, a latch engaging member carried by said bracket member, and a weight carried by said latch member, said weight causing said latch member to normally engage said latch engaging member to thereby maintain the gate in closed relation to said outlet port in the line of travel of said carriers, said latch having a trigger member arranged to be engaged by carriers of a certain class to prevent the engagement of said latch with said latch engaging member and allow the gate to be swung to open position by the impact of a carrier therewith.

50 5. A separator device for carrier dispatch mechanism having therein, in combination with carriers of different kinds and means for guiding them in a predetermined path, an abutment member projecting into the path of movement of the carriers and normally lying in a plane extending cross-wise of said path, but movable out of such path by the moving carriers, a fixed element, and means for limiting the movement of the abutment member by locking it to said fixed element whereby momentarily to arrest the movement of a part at least of the advancing end of the carrier.

55 6. A separator device for pneumatic carrier dispatch systems having therein, in com-

5 combination with carriers of different kinds and a tube guiding them in a predetermined rectilinear path, an abutment element normally extending cross-wise of the path of the carriers for engagement and movement thereby, and detector means operated by carriers approaching the abutment member having a part adapted to interlock with means fixed to said tube for limiting the movement of 10 the abutment member whereby momentarily to arrest the movement of a part at least of the advancing end of the carrier.

7. A separator device for pneumatic dispatch systems, comprising a tube having an 15 opening therein for the lateral discharge of carriers, an abutment element normally arranged within said tube and movable by contact with a carrier, said abutment being constructed and arranged to convert the rectilinear movement of an advancing carrier into a curvilinear movement toward and through said opening when movement of the abutment under impact of a carrier is obstructed, in combination with means for 25 positively locking the abutment to a fixed part of said device upon contact with said abutment of carriers of a certain kind.

8. Mechanism for assorting pneumatic carriers of different kinds successively moving 30 in a guiding tube comprising an abutment member normally projecting into the tube but movable therefrom, and means comprising a part normally positioned for interlocking engagement with a fixed element whereby substantial movement of the abutment member is prevented when engaged by an approaching carrier of one kind, said locking means being rendered inoperative by approaching carriers of another kind.

40 9. In combination with a pneumatic dispatch tube having a lateral discharge opening for the ejection of carriers, an abutment member normally extending across the tube near the lower edge of the opening in a 45 position to cause the center of gravity of an advancing carrier to describe a curvilinear path having its center at the point of contact of the advancing end of the carrier with the abutment member, and locking means having a fixed element for positively retaining said abutment in normal position but adapted to be rendered inoperative by carriers of a certain kind.

10. Carrier dispatch mechanism having 55 therein an assorting device for carriers of different kinds moving successively in a predetermined path, comprising a movable abutment member having a carrier engaging surface operatively positioned in a plane 60 substantially normal to said path and arranged momentarily to arrest a part at least of the advancing end of a carrier, a movable detector normally projecting into said path, and means normally operative positively to 65 detain the abutment member substantially

in normal operative position, said detaining means being rendered inoperative by a carrier of one of said kinds.

11. Selector mechanism for carrier dispatch systems comprising a lever abutment 70 member normally positioned to engage and arrest the movement of a part at least of the advancing end of a carrier, resilient means for retaining the abutment member in normal position, a latch member associated with the abutment member and engageable with a fixed element whereby positively to retain the abutment member in normal position and means actuatable by carriers of predetermined type for rendering the latch 75 member inoperative.

12. In combination with a pneumatic dispatch tube having a lateral discharge opening for the ejection of a carrier, a movable abutment member normally extending transversely across the tube for engagement with the advancing end of an approaching carrier, whereby to cause the following end of such carrier to describe an arc about the advancing end as a center in moving outwardly through the opening, and means for supporting such abutment under the blow of impact of an approaching carrier, said means comprising a fixed member and a 90 latch engageable therewith.

13. In combination with a pneumatic tube having a lateral discharge opening for carriers, an abutment lever pivotally supported at a point outside said tube and substantially opposite said opening, said lever having an arm projecting into said tube and terminating adjacent to said opening, a detector lever pivotally supported upon said lever arm and provided at one end with a detector element arranged within the tube 105 and projecting above said arm, said lever having a hook at its other end, and a fixed pin for engagement by said hook.

14. A carrier selector mechanism for use with pneumatic tube systems comprising a 110 supporting structure constructed and arranged for attachment to the extremity of a tube, a movable abutment supported thereon, detector means carried by the abutment, a fixed element, and a retaining device associated with said detector means and normally contacting with and positioned for operative interengagement with said fixed element for positively limiting movement of the abutment.

15. A carrier selector device for use with pneumatic tubes comprising a pair of spaced bracket members arranged in substantially parallel relation, an abutment lever mounted between said members and pivoted upon a pin extending transversely between said members, a detector lever pivoted upon said abutment lever and also arranged between the bracket members, and a latch hook associated with said detector le- 130

ver and engageable with a pin secured in the respective bracket members.

16. A selector mechanism having a lever comprising parallel spaced abutment elements, and a detector lever pivotally mounted upon said abutment lever and arranged in a plane intermediate said parallel elements, said detector lever being provided at one extremity with an upwardly directed 10 detector finger and at its other extremity with a downwardly directed hook, and a frame for supporting the parts having a fixed element to be engaged by said hook.

17. Selector mechanism for use with pneumatic tubes comprising a movable abutment normally disposed in the path of carriers passing along the tube, a latch element normally preventing movement of the abutment to more than a predetermined extent, means

actuable by certain carriers for rendering the latch element inoperative, and a shock absorbing device to limit movement of the abutment under impact of a carrier when the latch element has been released.

18. Selector mechanism for assorting carriers of different kinds passing through a guiding tube comprising a movable abutment member normally disposed transversely of the tube, a latch carried by the abutment and engageable with a fixed member 25 to limit movement of the abutment under impact of a carrier, means actuatable by certain carriers for rendering the latch inoperative, and buffer means for limiting movement of the latch when moved by a carrier 30 after the latch has been rendered inoperative.

JAMES G. MACLAREN.
